UNITED STATES PATENT OFFICE.

FRED SMITH DAVIS, OF MULLIGAN, SOUTH CAROLINA, ASSIGNOR OF
ONE-HALF TO JAMES CLARENCE RICHARDSON, OF ROBERTSVILLE,
SOUTH CAROLINA.

WOOD DISTILLING AND PRESERVING APPARATUS.

No. 826,407.

Specification of Letters Patent.

Patented July 17, 1906.

Application filed October 23, 1905. Serial No. 284,040.

To all whom it may concern:

Be it known that I, FRED SMITH DAVIS, a citizen of the United States, residing at Mulligan, in the county of Hampton and State of 5 South Carolina, have invented certain new and useful Improvements in Wood Distilling and Preserving Apparatus; and I do hereby declare the following to be a full, clear, and exact description of the invention, such as 10 will enable others skilled in the art to which it appertains to make and use the same.

My invention relates to an apparatus for use in the partial distillation of wood by a process which does not destroy the material 15 acted upon, but preserves it from injury and leaves it after the turpentine and other light oils have been recovered in condition for use in other relations, this application being an improvement upon my former patent, No. 20 774,649, dated November 8, 1904.

Further objects of my invention are to provide an apparatus having novel and advantageous heat-distributing means and an arrangement of retorts and other parts of the 25 apparatus conducive to economy of fuel and heat, as well as time and labor.

With these objects in view my invention consists of the construction and combination of parts, as hereinafter described and claimed.

In the accompanying drawings, Figure 1 shows a plan view, partly in section, showing the apparatus and sections of track leading into the retorts; and Fig. 2 is a side elevation of the same, one of the retorts being removed.

Fig. 3 is a cross-section through the retorts, showing the furnace in full lines. Fig. 4 is a bottom plan view, on an enlarged scale, of the centrifugal pump-runner; and Fig. 5 is a cross-section, on an enlarged scale, of the 40 tank, showing the centrifugal pump in position therein.

Briefly, the apparatus includes an arrangement of retorts which are first charged with the wood to be treated and then filled with a 45 heated fluid, which fluid extracts the turpentine and other light volatile oils without injuring in the slightest degree the texture of the wood itself, the heat being kept entirely too low to permit of any destructive distillation.

In order to maintain the heat in any one of the retorts at the required degree, provision is made for forcibly circulating the preserving 50 fluid through a reheat and back again

through the retort, this method being preferable in my opinion to the application of 55 heat directly to the retort itself. These retorts are preferably arranged in pairs and provided with connections so arranged that one retort may be cleaned and recharged while the other is being operated, thus effecting 60 a great saving in time and obviating the need of repumping to and from the main source of supply of the distilling and preserving fluid for each charge. In connection with the retorts there are used a furnace and 65 tank for initially reducing the preserving and distilling fluid to a liquid form and a pump for delivering said fluid from said tank to either or both of a pair of retorts, although it is obvious that more than two retorts could be used, if desired. A pump of any approved 70 design, but preferably a rotary pump, and a reheat are also used, said pump, reheat, and pair of retorts being connected by pipelines suitably valved, so that the distilling 75 and preserving fluid may be circulated through the pump, heater, and either retort, as desired. From each retort leading back into the tank is a valved discharge-pipe, so that the preserving fluid may be allowed to 80 run back into the tank when the material in the retort has been fully treated or when for any reason it is desired to shut down—as at the end of the week, for example. Each retort is provided with one or more condensing- 85 hoods, two being preferably used for each retort for receiving the gases given off, and suitable pipes lead from said hoods to a condenser of approved type, which has a vacuum-pump arranged at its outlet, so that air may 90 be pumped through the apparatus and the condensation thereby aided.

I have found by experiment that excellent results have been obtained by using melted 95 rosin as the distilling and preserving fluid, and in the following description such fluid will be referred to as "rosin," but the process is not limited to this especial preservative, as tar, pitch, creosote, or any other of the well-known preservatives for wood may also be 100 advantageously used, and the apparatus is equally well adapted to the use of any of them.

Referring to the drawings, 1 and 2 represent a pair of retorts which are preferably of 105 a size to conveniently contain a truck loaded

with pine wood, although they may be of any convenient or desirable size, and into these retorts lead the tracks 3, on which the trucks are run. The walls of the retorts are preferably constructed of brick and cement and are made double—that is to say, there is an inner wall and an outer wall with an air-space between. The retorts, however, may be constructed of any desired material, and I have found in practice that a construction lined with sheet-iron gives very good results. The air-space between the walls of the retort is preferably connected with the outer air by means of the small holes 4, through which sand is poured for the purpose of sealing up any cracks that may occur in the retort-walls. These air-holes and spaces are shown at 45 in Fig. 3, 46 representing the sand.

Conveniently located with relation to the retorts and preferably with its top below the level of the floor of the retorts is a tank 6, used as a melting-tank for the rosin to be pumped into the apparatus. The tank is mounted below the level of the retorts, so that the melted rosin will flow back by gravity into the tank when the apparatus is shut down. The tank is suitably mounted within a furnace 7 of any desired construction provided with a stack 8. The tank 6 should be of such a size that it will hold enough rosin to entirely submerge a loaded truck in one of the retorts.

Within the tank 6 is mounted a centrifugal pump 9, which may be driven by means of a pulley 10, mounted on a shaft 11, projecting down through the top of the furnace. This pump delivers into a pipe 12, which has branches 13 and 14 delivering into the retorts 1 and 2, said branches being provided with valves 15 and 16.

In Fig. 5 is shown the tank and centrifugal pump on an enlarged scale, and in Fig. 4 is shown the bottom of the preferred form of pump-runner. The shaft 11 is supported by a step 46, bolted or otherwise secured to the bottom of the tank. A pump-casing 47 is secured, by means of braces 48, to the walls of the tank. The preferred form of centrifugal pump which I use consists of a disk 49, with a recess 50 in its edge fitting a corresponding rib in the casing 47, said disk being provided on the under side with curved wings 51 and on the upper side with curved wings 52, arranged, however, in the opposite direction. The disk 49 is perforated, as shown at 53, for the passage of the melted rosin up therethrough. It is obvious that when the shaft 11 is revolved the wings 51 will force the melted rosin up through the holes 53 and that the wings 52 will force it out through the pump-casing into the pipe 12.

From the construction shown it is obvious that a constant circulation and stirring action takes place at or near the bottom of the tank, thus preventing sedimentary deposits

and keeping the entire mess of liquid in the tank thoroughly stirred up. This pump therefore has a double function—namely, it forces the melted material into the retorts and it keeps the material in the tank thoroughly stirred up. Another advantage of this form of pump located within the tank itself and near its bottom is that the pump is always submerged in the fluid and needs no priming.

Obviously by the construction described the rosin may be delivered from the melting-tank into either or both of the retorts 1 and 2.

17 and 18 represent gravity discharge-pipes leading from the retorts 1 and 2 back into the tank 6, said pipes being provided with valves 19 and these pipes being used when it is desired to shut down the apparatus.

Located between the retorts is a pump 20 of any suitable design which is connected, by means of pipes 21 and 22, with the retorts 2 and 1, these pipes being provided with valves 43 and 44, respectively. The pump 20 may be of any suitable design; but I found a rotary pump to be satisfactory in use. Connected to the pump 20 is a pipe 23, which passes into a reheater 24, located within a furnace 25. The reheater 24 is provided with a discharge-pipe 26, which is connected with branch pipes 27 and 28 with the retorts 1 and 2, these pipes being provided with valves 29 and 30. Provision is made for the reception of thermometers 31 in the pipes 21, 22, 27, and 28. The purpose of these connections is that the rosin may be pumped through one or both of the retorts passing on its way through the reheater. In this way the rosin is kept at the desired temperature without the direct application of heat to the retorts.

32 and 33 represent condensing-cones connected to the tops of the retorts 1 and 2, which cones are connected by suitable valved pipes 34 and 35 to a condenser-coil 36, located in a tank of water or other cooling material 37. The condenser-coil delivers its products into any suitable receptacle, such as a barrel 38, on which is mounted a vacuum-pump 39, driven by a pulley 40 from any suitable source of power. The collecting-receptacle 38 is provided with an outlet 42, which in turn is provided with a seal, as is customary. The pump 39 should not be of sufficient power to lift the condensed products or to draw the gases through the condensing-coil before they are condensed.

The operation of my device is as follows: A truck loaded with wood is pushed into one of the retorts—say the retort 1—and the door 41 thereof closed and sealed, a fire having been previously started in the furnace 7. Melted rosin is then pumped through the pipes 12 and 13 into the retort 1 until the charge of wood has been completely submerged, the valve 19 in the pipe 17 having first been closed. After the full charge of rosin has been pumped into the retort 1 the

valves 15, 44, and 30 are closed, the valves 43 and 29 opened, and the pump 20 set in operation, the reheater 24 having first been heated by a fire in the furnace 25. A continuous flow of rosin then takes place from the retort 1 into the pump 20 and through the reheater 24 back into the retort 1, thus maintaining the charge of rosin at the desired temperature without directly heating the retort 1, the charge of rosin being kept at the proper temperature by the manipulation of the fire in the furnace 25, the temperature being observed by means of the thermometers 31. The hot rosin drives off the gases from the wood, which gases rise into the cones 32 and 33 and then pass into the condensing-coil, the volatile products being collected in the receptacle 38. The temperature is regulated carefully, so that the fiber of the wood is not injured, being kept below the point where destructive distillation begins. All the light products, including the turpentine, rosin, and other light oils, are extracted from the wood, leaving it unharmed. While this operation is going on in retort 1, retort 2 has been charged with wood. As soon as the operation is finished in retort 1 the valve 29 is closed and the valve 30 opened. The pump 20 being kept in operation, the charge of rosin is pumped from retort 1 into retort 2, and after the full charge has been pumped over the valve 43 is shut and the valve 44 opened, the circulation of the hot rosin through the pump 20 and reheater 24 being the same as already described. The rosin is never run back into the tank 6 except for the purpose of a shutdown, and the operation is therefore practically continuous.

While I have thus described my invention, I wish it to be distinctly understood that I do not limit myself to the exact details shown and described; but

What I claim, and desire to secure by Letters Patent, is—

1. In an apparatus of the character described, the combination of a retort for the reception of the material to be treated, a furnace and tank for melting the material used as a distilling fluid, a centrifugal pump located at or near the bottom of said tank, said pump serving to discharge the melted fluid into the retort and also to keep the fluid in the tank thoroughly agitated, a valved pipe connecting said pump with said retort, and a

valved discharge-pipe connecting said retort with said tank, substantially as described.

2. In an apparatus of the character described, the combination of a retort for the reception of the material to be treated, a furnace and tank for melting down the material used as a distilling fluid, a centrifugal pump located near the bottom of said tank, said pump serving not only to discharge the melted fluid from said tank to said retort, but also to keep the material in said tank thoroughly agitated, supply and return connections between said pump and said retort and said tank, and means for maintaining the charge of distilling fluid in said retort at an even temperature, said means including a pump, a reheater, and pipe connections between said retort, pump and reheater, substantially as described.

3. In an apparatus of the character described, the combination of a battery of retorts, a suitable furnace and tank for melting down the material used as a distilling fluid, a centrifugal pump in said tank located at or near the bottom thereof, said pump serving to keep said material thoroughly agitated, a valved branched pipe leading from said pump to each of said retorts, and valved gravity return-pipes leading from said retorts respectively back into said tank, substantially as described.

4. In an apparatus of the character described, the combination of a battery of retorts, a suitable furnace and tank for melting down the material used as a distilling fluid, a centrifugal pump mounted in said tank at or near the bottom thereof and serving to keep the material in said tank thoroughly agitated, a valved pipe connected with said pump and provided with branches, one of said branches leading to one of said retorts respectively, a valved return-pipe leading from each of said retorts respectively to said tank, and means for maintaining the charge of melted fluid in either of said retorts at a constant temperature, consisting of a pump and reheater, and valved pipes connecting said retorts with said pump and said reheater respectively, substantially as described.

In testimony whereof I affix my signature in presence of two witnesses.

FRED SMITH DAVIS.
